RAILWAY SIGNALING SYSTEM

Georges Caille, Vaujours, France, assignor, by
mesne assignments, to The Union Switch &
Signal Company, Swissvale, Pa., a corporation
of Pennsylvania

Application March 18, 1932, Serial No. 599,705
In France March 20, 1931

3 Claims. (Cl. 246—3)

This invention relates to railway signaling systems of the kind comprising track circuits constituted by the track rails which are subdivided into block sections provided with the usual signals 5 for the control of traffic through the section. The operation of the signals is controlled by line relays and track relays in accordance with traffic conditions in advance and the invention has for its principal object to provide a system of the general 10 character above described in which the number of line wires extending along the track is reduced to a minimum, a further object of the invention being to prevent improper operation of the signals in the event of accidental contact between the line 15 wires. A still further object of the invention is to provide means whereby the signals are only rendered operative for a predetermined distance along the track in advance of a train.

The invention is illustrated in the accompanying drawing which is a diagrammatic view of the general arrangement and circuit connections of a section of track provided with signals controlled in accordance with one form of the invention.

Referring now to the drawing, the track rails 20 are indicated at d , d' , and are divided by insulating joints i into a plurality of block sections 1 , 2 , and 3 , through which traffic proceeds in the direction indicated by the arrow. At the entrance end of each block section a signal S_1 , S_2 , or S_3 is provided, these signals being of the illuminated or light type and each comprising a green or proceed lamp v , a yellow or caution lamp j , and a red or stop lamp r . In addition each or certain of the signals may comprise a pair of red lamps r^x which 25 when illuminated indicate absolute stop as shown in the case of the signal S_3 .

Each block section is provided with a track relay such as VB_1 , VB_2 , or VB_3 , respectively, connected across the track rails and a line relay such 30 as LB_1 , LB_2 , or LB_3 , respectively, controlled by the corresponding track relay.

In accordance with one feature of the invention, each block section is provided with an approach line relay such as APL_1 or APL_2 , respectively, connected 35 in series with the corresponding line relay by line conductors such as l_1 , l_1' . The circuit comprising each line relay LB and the associated approach line relay APL is controlled by an associated approach track relay APV , as well as by the track 40 relays VB of the corresponding section and of the section in advance. Each approach track relay APV is connected across the track rails of the section in series with a track battery b , and each 45 circuit including the relays LB and APL is sup-

plied with current from the terminals a , a' of a suitable source.

The operation of the system is as follows:

(a) *Signal control by train*

Let it be assumed that the block section 3 is occupied by a train or vehicle. The track relay VB_3 is deenergized owing to the presence of the train or vehicle and the relay contacts 10 are consequently opened so that the supply of current to the line relay LB_2 of the section 2 is interrupted. The contact 11 of line relay LB_2 therefore falls to its lower position and completes a circuit from terminal a through contact 13 (closed as will be explained later by the approach of another train), contact 14 (which is in its upper position since track relay VB_2 is energized), contact 11 of relay LB_2 (which is in its lower position), caution lamp j of signal S_2 , to the other terminal a' .

The signal S_2 will thus be prepared to give a caution indication to a train entering the section 1 as will be explained hereinafter while as regards signal S_3 , the track relay VB_3 is deenergized by the presence of the train in section 3 and the contact 14 of this relay being in its lower position, the circuit of the stop lamp r of signal S_3 is prepared to give a stop indication to the following train.

The system illustrated is provided with a central control relay LC the contacts 17 of which are included in the circuit of the relays LB_2 and APL_2 , the energizing circuit of the relay LC including contacts 16 , $16'$ operated by switch levers 15 , $15'$ at the control cabin, this arrangement being provided for enabling an operator at the cabin to place the signal S_3 to stop if desired by lighting lamps r^x through back contact 30 .

Under the conditions above described, however, the circuit of the relays LB_2 and APL_2 is interrupted at the contacts 10 of track relay VB_3 so that the setting of the switch levers 15 , $15'$ by the operator is immaterial.

(b) *Approach control of signal indications*

The signals corresponding to block sections at a distance to the rear of the occupied section are arranged to be automatically illuminated when a train approaches, this being effected by the action of the line approach relays APL in the following manner.

Let it be assumed that a train is entering block section 2 . The track relay VB_2 will be deenergized so that the relay contact 18 will fall to its lower position. The approach line relay APL_2 will thus be deenergized and its contact 13 will

close, thus finally completing the lamp circuit of the signal S_3 and causing one or another of the signal lamps of the signal S_3 (as determined by the relays VB_3 , LB_3 , and LC) to be illuminated. 5 The control of lamps v , j and r of this signal is in accordance with usual practice and need not be explained in detail herein.

(c) *Locking of central control by approaching train*

10 The relay APL_1 comprises in addition to relay contact 13 , relay contacts 19 , $19'$ included in the energizing circuit of an approach locking relay EA at the signal cabin at a station for instance, 15 the relay EA preventing the operator from throwing the switch levers 15 , $15'$, so as to give a stop signal indication at the last moment to a train which is too near to the station, the relay EA being of course only effective for this purpose if 20 the block section adjacent to the station is unoccupied.

Let it be assumed that a train is entering block section 1 ; relay VB_1 being thereby deenergized, the opening of relay contact 18 will deenergize 25 relay APL_1 , the relay contacts 19 , $19'$ of which accordingly open. Locking relay EA , is therefore, deenergized and the opening of its contact 20 causes a visible or audible indicator E_1 to be operated. The deenergization of the relay EA 30 also causes a relay contact 22 to open which deenergizes an electric locking device 23 . The latter when deenergized locks the switch levers 15 , $15'$, and prevents the operator from causing a stop signal to be given by the signal S_3 . 35 If however when the train enters section 1 , another train is already occupying block section 3 , the action above described does not take place since track relay VB_3 is deenergized by the presence of a train in block section 3 and contacts 24 , $24'$ of the relay VB_3 are in their lower position in which a supply of energizing current to the relay EA is provided through a circuit not including the open contacts 19 , $19'$.

45 (d) *Control of track contact*

Each block section is shown as provided with a track contact device C_1 , or C_2 , for repeating the signal indication on the locomotive.

Let it be assumed that block section 3 is occupied but that block section 2 is unoccupied; relays VB_3 and LB_2 are deenergized and contact 50 25 of relay LB_2 is thus closed. A circuit is thus completed from terminal a to contact device C_1 , thence through a suitable indicating device on the locomotive (not shown), track rail d' , contact 25 and contact 31 of relay VB_2 (closed since relay VB_2 is energized) to the other terminal a' . An indication is thus given on the locomotive that 55 block section 2 is unoccupied.

60 If, however, block section 2 is occupied, relay VB_2 is deenergized and relay contact 31 would be open so that current is not supplied to the track contact C_1 and a corresponding indication is given on the locomotive.

65 Let it be now assumed that a contact is effected accidentally between the line wires l , l' , for example at the point x in block section 1 , and that a train enters this block section. If the approach track relay APV_1 were not provided the 70 opening of contact 10 of the relay VB_1 owing to the deenergization of this relay by the train entering block section 1 would not effect the deenergization of the relay APL_1 since the energizing circuit of this relay would remain completed through contacts 10 of relay VB_2 , the point of ac-

75 cidental contact x and the winding of the relay APL_1 . As a result the signal lamps of the signal S_2 at the entrance to the block section 2 would not be illuminated since the contact 13 of relay APL_1 would not close, while locking of the switch levers 15 , $15'$, would also not occur since the contacts 19 , $19'$ of relay APL_1 would not open and the relay EA would remain energized.

To remedy this disadvantage and to avoid all possibility of non-agreement between the positions of the relays coupled together in the same block section, the approach track relays APV_1 , APV_2 are provided in accordance with the invention, each of these relays being arranged as shown to control the corresponding approach line relay 15 in the same manner as this latter relay is controlled by the corresponding track relay VB .

As above stated and as illustrated in the drawing the approach track relay APV is connected across the track rails d , d' , of the block section 20 in series with the battery b , which also serves as a track battery for the corresponding track relay VB . The resistance of the energizing winding of the relay APV is so proportioned relative to the voltage of the battery b , that when as is the 25 case under normal conditions, the two relays APV and VB are in series with one another, the sum of the resistances of their energizing windings is too large for the current circulating in the windings of the relays to be sufficient to operate 30 the relay APV , this current being however sufficient to energize the track relay VB . When however a train enters the block section 2 , the relay VB is short-circuited and the consequent decrease in the resistance of the circuit causes the 35 current traversing relay APV to increase to such a value that this relay is operated. It will thus be seen that the relays APV are normally deenergized, whilst the track relays VB are normally energized, each of the relays APV , being only 40 energized when a train enters the corresponding block section and short-circuits the corresponding relay VB . If therefore a train enters block section 1 , whilst a contact is established at x between the line wires l , l' , the energization of 45 relay APV_1 opens the relay contacts 26 so that the energizing circuit of relay APL_1 is interrupted in spite of the accidental contact at x .

From the above description it will be apparent that the invention as illustrated enables 50 the following control conditions to be obtained with only two line wires.

1. A stop signal indication to be given by the illuminated or other signal protecting a block section which is occupied.

2. A caution signal indication to be given at the signal to the rear of the signal displaying a stop indication.

3. A proceed signal indication to be given at the signal to the rear of the signal displaying 60 the caution indication.

4. The track contact device is rendered effective when a signal is displaying a caution indication.

5. The light signal is arranged to be illuminated by the entrance of the train into the block section preceding the signal.

6. The locking of the signal control by the operator when a train is approaching.

All or certain of these conditions may be embodied in a signaling system incorporating the invention and the system may also comprise additional controlling arrangements or devices as may be required to effect the control of traffic in any particular case.

Having now described my invention, what I claim as new and desire to secure by Letters Patent, is:—

1. In combination, a section of railway track, 5 a track circuit for said section including the usual source of current and the usual normally energized track relay, an approach track relay interposed between said source and one of the rails and normally deenergized but arranged to 10 become energized when a train occupies the section, an approach lighting relay, a circuit for said approach lighting relay including a front contact of said usual track relay and a back contact of said approach track relay, and a signal 15 in advance of said section having a lighting circuit including a back contact of said approach lighting relay.
2. In combination, a stretch of railway track divided into sections, a track circuit for each 20 section including the usual source of current and the usual normally energized track relay, an approach track relay for each section interposed between said source and one of the rails and normally deenergized but arranged to become 25 energized when a train occupies the section, a line relay and an approach lighting relay for each

section, a line circuit for each section including the associated line relay and approach lighting relay and controlled by a front contact of the associated usual track relay and a back contact of the associated approach track relay as well as by a front contact of the usual track relay for the section next in advance, and a signal for each section controlled by the associated track relay and line relay as well as by the approach lighting relay for the section next in 10 the rear.

3. In a railway signaling system, the combination of a section of railway track; a signal for said section, capable of displaying an absolute stop indication; means for automatically controlling said signal in accordance with traffic conditions in said section, manually controlled means for causing said signal to display said absolute stop indication, and means operated by the approach of a train within a predetermined distance from said signal for rendering said manually controlled means inoperative to cause said signal to display said absolute stop indication.
